UNITED STATES PATENT OFFICE.

WALTER A. BARROWS, OF BELVIDERE, ILLINOIS.

TRUSS.

1,408,683.

Specification of Letters Patent.

Patented Mar. 7, 1922.

Application filed April 21, 1919. Serial No. 291,699.

To all whom it may concern:

Be it known that I, WALTER A. BARROWS, a citizen of the United States, residing at Belvidere, in the county of Boone and State of Illinois, have invented certain new and useful Improvements in Trusses, of which the following is a specification.

My invention relates to improvements in trusses and has for its general objects to provide an improved and simple construction for the reliable and efficient application of requisite pressure with maximum comfort to the wearer, to attain simplicity, economy and durability in construction, and to afford maximum effective adjustment to insure exact application of the pressure over the desired area and with the front pressure pads angularly positioned for best results.

My invention consists in the features of construction and arrangement of parts hereinafter claimed, and may satisfactorily be embodied in the form shown in the accompanying drawings wherein I have illustrated only a single construction involving the invention for purposes of disclosure.

In the drawings Fig. 1 is a front elevation of a truss embodying my invention; Fig. 2 is a longitudinal section of one of the front pads; Fig. 3 is a rear elevation of one of the back pads; Fig. 4 is a longitudinal section through such back pads; and Figs. 5, 6 and 7 are details of a front pad adjusting means.

The back spring 10, preferably a broad, thin spring-metal strap, connects at opposite ends with the back pads 11, to which are connected the side springs 12, each preferably a rather narrow thick spring shaped in suitable sweeping curves with a down-turned end 13, so that the side springs may pass over the hips to about the areas for front pad pressure application. The angle of the side springs to the back spring may be varied as follows: Each back pad involves a cupped base plate 14 with an out-turned smoothly curved flange 15, the surface of the base plate for contact with the wearer being covered, as by a leather piece 16 or a piece of other suitable material suitably gathered over the flanged edges and into the inside of the cup-like plate. The cover may be held in place in any suitable fashion as by a pucker-spring (not shown), cementing, or the pressure of the complementary cover plate to be described. Preferably the flange 15 is cut away as at 17 at a suitable point to re-

ceive and position the relatively thick and narrow side spring, and at its center it is countersunk as at 18 to receive exteriorly the shallow head of a bolt 19 soldered or otherwise suitably secured in the base plate and interiorly to provide a central boss. Over this bolt is placed an apertured cupped cover plate 20, having an edge flange 21 to enter inside of the flange 15 of the base plate, this flange 21 being notched as at 22 and 23 to receive the back band 10 and the side spring 12 and give definite position to their points of egress from the pad. At the center the cover plate is countersunk as at 24 throughout a sufficient area to receive exteriorly the nut 25 and interiorly to form a flat-topped boss. The side spring arm 12 is provided with a series of holes 26 to receive the center bolt 19, and back spring 10 is provided with a plurality of slots 27 also to cooperate with said bolt. The parts may be assembled with the bolt engaging any one of the holes of the side spring and any slot of the back strap, for length-adjustment and— 80 rocking on the edge of cover-plate notch 22 to bring the bolt 19 to different positions in spring-slots 27—the back strap may have its angular relation to the side spring 12 varied through a considerable range, adequate for vertical adjustment purposes to bring the front pads to just the proper elevation. When the desired length and angle have been determined the nut 25 is tightened, clamping the two spring members 90 tightly between the inwardly extending bosses formed at the countersunk portions of the two plates.

Each front pad as illustrated in Figs. 2 and 5 to 7, preferably comprises a yielding 95 cushion of rubber or other suitable material, of suitable shape, the convex body 30 being formed with a recess at its outer side or base adapted to receive a removable base plate 31 of sheet metal having preferably a slight 100 out-turned flange or lip 32 (the recess being formed of corresponding shape), and having also a central screw-threaded hub or boss 33. When the base plate 31 is seated in the body 30, the body material extends back in 105 a layer 34 into the interior of the slightly cupped plate. A cover plate 35 of suitable material, such as sheet metal, and formed with an in-turned edge flange 36, is mounted with its edges bearing on the yielding layer 110 34 aforesaid, and its central part spaced from the base-plate, so that, through the

springiness of the cover plate, or the springiness of the layer 34 or (preferably, and as herein shown) by both these spring elements, the center of the cover plate is resilient enough for spring-clutch purposes. Around the center of such plate are made a series of clutch-tooth-indentations 37, and for cooperation therewith I arrange a sheet-metal companion member or saddle 38 with a circle 5 of projecting teeth 39, out-pressed therefrom, this member having at one edge upturned lugs 40 to straddle the downturned end 13 of the side spring 12 so that the saddle may not turn on the spring-arm. The 10 coacting members are suitably apertured to receive a retaining screw 41, and the end of the spring arm 12 has a plurality of apertures 42 any one of which may receive the screw, for length-adjustment of the pad on 15 the arm. A connecting strap 43 is used to prevent the pads from spreading apart. The construction and arrangement of the parts in such that by extreme adjustment of the screw the parts may be immovably secured 20 together, but in practice the adjustment is preferably such that the pad will be adequately held against accidental displacement while capable by manipulation of rotary adjustment, the pad snapping from point to 25 point as it is rotated, with the plate 35 yielding so that the indentations 37 may ride over the teeth 39.

The desirable facility of adjustment, with certainty of maintenance of adjustment, will 30 be apparent, and the simplicity and economy of the device from a structural point will be clearly understood by those skilled in the art.

While I have herein described in some detail a particular embodiment of my invention, it will be understood that in some features departures may be made from the specific structure shown without departure from the spirit of my invention and within 40 the scope of the appended claims.

45 What I claim is:

1. A truss having a back spring, back pads, side springs and front pads, one of said back pads comprising front and back plates, one thereof having notched edges to 50 relatively position the points of egress of the back and side springs, and a bolt for connecting said plates, one of said springs being connectible with said bolt for longitudinal adjustment and the other connectible with 55 said bolt for lateral adjustment.

2. A truss having a back spring, back pads, side springs and front pads, one said back pad comprising front and back plates, having edge-notches to relatively position 60 the points of egress of the back and side springs, and a bolt for connecting said plates, one of said spring members being connectible with said bolt for longitudinal and lateral adjustment.

65 3. A truss having a back spring, back

pads, side springs and front pads, one of said back pads comprising front and back plates, one thereof having notched edges to relatively position the points of egress of the back and side springs, and a bolt for 70 connecting said plates, one of said members being connectible with said bolt for lateral adjustment and said members being capable of connection in fixed relation by the tightening of the bolt.

4. In a truss, the combination of a relatively broad thin back-spring having a plurality of slots extending transversely near its end, a relatively narrow thick side spring having a plurality of apertures near its end, 80 and a back pad structure adjustably connecting the two comprising a base plate, a cover plate, said plates having interfitting flanges suitably notched for passage of the said springs, and a bolt connecting said plates 85 and passing through selected ones of the slots and holes in the said two springs, for adjustment of the springs as to extension and angle.

5. In a truss, the combination with a 90 spring arm, of a front pad comprising a body, a base plate attached thereto, a cover plate yielding with respect to the base plate and having a toothed portion, a headed stem passing through the toothed plate and the 95 spring arm, and a member encircling said stem and non-rotatably engaging the spring arm provided with a toothed portion complementary to that of the pad-plate, said member being yieldingly confined between 100 said cover plate and the head of said stem.

6. In a truss, the combination with a 105 spring arm of a front pad comprising a resilient body, a base plate embedded in said body and at its outer side partly overlain by the resilient material, a cover plate bearing on the center overlying portion of said resilient material and centrally yieldable with respect to the base plate, a stem engaging the base plate and extending through said 110 cover plate and at its outer end engaging said spring arm, a saddle member surrounding said stem interposed between the spring arm and said cover plate and non-rotatable 115 with respect to the spring arm, said member and cover plate having complementary toothed portions for positioning them effectively in desired angular relation, said cover plate yielding to permit the teeth to be 120 snapped past each other.

7. A truss having a resilient back spring member, side springs connected to said back spring member and angularly adjustable with respect thereto, back pads intermediate 125 said back spring member and side springs, front pads secured at the forward ends of said side springs, and a strap connecting said front pads.
